(57) **CLAIM**

We claim the ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof;

FIG. 13 is the thirteenth image thereof;

FIG. 14 is the first image in a sequence for a display screen or portion thereof with animated graphical user interface in which various environmental features are removed;

FIG. 15 is the second image thereof;

FIG. 16 is the third image thereof;

FIG. 17 is the fourth image thereof;

FIG. 18 is the fifth image thereof;

FIG. 19 is the sixth image thereof;

FIG. 20 is the seventh image thereof;

FIG. 21 is the eighth image thereof;

FIG. 22 is the ninth image thereof;

(Continued)

FIG. 23 is the tenth image thereof;
 FIG. 24 is the eleventh image thereof;
 FIG. 25 is the twelfth image thereof; and,
 FIG. 26 is the thirteenth image thereof.
 The broken line rectangle illustrates a display screen. The remaining broken lines illustrate portions of a graphical user interface, and, in FIGS. 1-13, a mobile electronic device. The broken lines form no part of the claimed design.
 The appearance of the animated user interface sequentially transitions between the images shown in FIGS. 1-13 and FIGS. 14-26. The process or period in which one image transitions to another forms no part of the claimed design.
